Fig. 6

FIG. 1 is a top plan view of a reed for a reed switch showing my new design;

FIG. 2 is a side elevational view thereof;

FIG. 3 is a top plan view of a modified form of the reed described in FIG. 1 showing my new design;

FIG. 4 is a top plan view of a modified form of the reed described in FIG. 1 showing my new design;

FIG. 5 is a front side elevational view thereof; and

FIG. 6 is a top plan view of a modified form of the reed described in FIG. 1 showing my new design.

The bottom plan views opposite to the top plan views of FIGS. 1, 3, 4 and 6 are identical to these respective figures. The other side elevational views of the reeds shown in FIGS. 1 and 3 are identical to FIG. 2. The left and right side elevational views of the reeds shown in FIGS. 4 and 6 are identical to FIG. 2. The rear side

elevational view of the reeds shown in FIGS. 4 and 6 are identical to FIG. 5. FIGS. 4 and 6 are broken away at one end to show indeterminate length. The tongues of FIGS. 1, 3, 4 and 6 include areas on either side thereof concavely depressed from the planar surface.

I claim:

The ornamental design for a reed for a reed switch, as shown and described.
